US0D1059320S

(12) **United States Design Patent** (10) **Patent No.:** **US D1,059,320 S**
(45) **Date of Patent:** **** Jan. 28, 2025**

(54) **COMBINED WIRELESS CHARGER AND PHONE STAND**

(71) Applicant: **Shaojun Tang**, Guangdong (CN)

(72) Inventor: **Shaojun Tang**, Guangdong (CN)

(**) Term: **15 Years**

(21) Appl. No.: **29/905,566**

(22) Filed: **Oct. 23, 2023**

(51) **LOC (15) Cl.** **14-06**

(52) **U.S. Cl.**

USPC **D14/251**; D13/108

(57) **CLAIM**

The ornamental design for a combined wireless charger and phone stand as shown and described.

DESCRIPTION

FIG. 1 is a front, right and top perspective view of a combined wireless charger and phone stand, showing my design.

FIG. 2 is a rear, left and bottom perspective view thereof.
FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the combined wireless charger and phone stand that form no part of the claimed design.

1 Claim, 8 Drawing Sheets
